UNITED STATES PATENT OFFICE.

JACOB WIDMER, OF NEW HARTFORD, CONNECTICUT.

SPINNING.

SPECIFICATION forming part of Letters Patent No. 700,272, dated May 20, 1902.

Application filed April 19, 1901. Serial No. 56,605. (No model.)

To all whom it may concern:

Be it known that I, JACOB WIDMER, a citizen of the United States, and a resident of New Hartford, in the county of Litchfield and State 5 of Connecticut, have invented certain new and useful Improvements in Spinning, of which the following is a full, clear, and exact description, whereby any one skilled in the art can make and use the same.

10 My invention relates to the art of spinning fibers of various material into the form of a thread, and more particularly to the guide or tension device by the use of which the fibers are twisted and then wound upon a bobbin, 15 as exemplified in the ordinary form of ring-spinners.

10 The object of my invention is to produce a guide by means of which improved results in the mechanism of spinning, in the art, and in 20 the resulting thread are obtained as compared with the prior art.

Referring to the drawings which form part hereof, Figure 1 is a view in elevation of a spindle, bobbin, and part of a spinning-frame. 25 Fig. 2 is a plan view of one form of embodiment of my invention, the guide-supporting ring being cut away in part and the spindle and bobbin shown in section. Fig. 3 is a view in central section of the guide and its supporting-ring.

30 In the accompanying drawings only so much of the mechanism of a spinning-frame is shown as is required to illustrate the relative location and manner of operation of one form of embodiment of my invention, and in these drawings the letter *a* denotes a spinning-spindle mounted in a spindle-rail *b* of any ordinary form of spinning-frame, the spindle being driven by a band *c* from any suitable drum 35 or pulley in the usual manner.

40 A ring *d* is mounted in a ring-rail *e* and serves as a frame to locate the guide *f* and to support it when in a position of rest, the guide being located in a groove *d'*, formed in the 45 inner surface of the ring. The ring is located in an opening in the ring-rail, and the spindle-blade extends through this opening and supports the bobbin *g*, the center of the ring coinciding substantially with the axis of the 50 spindle when the parts are at rest.

The guide *f* is preferably annular in form and has guide-arms *f'* *f''*, in which eyes or

loops for the reception of the thread are formed. These guide-arms are located on opposite sides of the guide-ring, although not necessarily diametrically opposite each other, but in such relation that the drag or tension on the thread *h* as it is wound upon the bobbin (see Fig. 2) may be utilized to balance the lateral pull upon the spindle in winding 60 the thread upon the bobbin. This guide *f* is practically suspended on the thread *h*, which extends downward to the guide (see Fig. 1) and passes through the eye in the guide-arm *f''* and the eye in the guide-arm *f'* before 65 winding upon the bobbin. This arrangement balances the guide, as well as suspending it, so that in winding no other support for the guide is required, and there is practically no rubbing contact of the guide with the walls 70 of the groove in the ring *d*.

By the term "groove" any form of recess in the ring *d* or within guiding-walls is designated.

Owing to the fact that ring-spinners as now 75 extensively used are fitted to support a ring in the ring-rail, the form of ring with its guide-holding socket as shown is preferred to enable my invention to be easily and cheaply adapted in a practical form to existing frames 80 and methods of operation, but is by no means limited thereto.

It is preferred that at least one of the guide-arms, as *f''*, shall be made long enough to be flexible and also to be of spring metal, as it 85 will then yield slightly under the drag or tension on the thread in winding and tend to equalize the tension as well as to prevent in a great measure the accidental breaking of the thread, which might occur were the guides 90 more rigid.

In the use of my improved guide in spinning thread the drag or tension on the yarn is substantially uniform under all the variation in diameter of the bobbin as the thread 95 mass builds upon it, and this is a great advantage over the old form of ring-traveler guide in common use. In the latter the tension is almost to the breaking point of the yarn when the thread first winds upon the bobbin, owing 100 to the angle of the draft and the resistance of the traveler to motion along the ring which supports it, and this tension grows less as the angle increases by the building up of the

thread mass on the bobbin, resulting in a variation in strength of the thread along its length. Another advantage from the use of my new guide is that thread of the same material and size and with spindles running at the same speed is wound upon bobbins of same size to an amount almost twice as great for the same diameters as compared with a thread mass wound on the same bobbin by the old devices—that is, the thread is wound more compactly by the use of my device. Another advantage is that there is an increase in tensile strength in the thread wound by the use of my new guide as compared with the old, actual tests showing a gain of from twenty-five to thirty-two per cent. Owing to the fact that the greater length of thread is wound by the use of my new guide, the bobbins need not be doffed as often, and in this regard a saving in time of nearly fifty per cent. has been shown, only thirty minutes per day in place of one hour being required. A still further advantage is found in the cheapness of construction of the new guide and its support as compared with the ring and its traveler. These advantages and several others flow from the use of my new guide, which is balanced and practically independent of any support in use other than the thread which is wound by its use, and it may be termed a "suspended" guide to distinguish it from those of the prior art, which require a positive support and guide distinct from the thread—as, for instance, the flanged

ring for the well-known traveler mounted 35 on it.

My invention is capable of various modifications and changes from the form herein shown without the exercise of more than the accumulated skill of the art, and such variations are within the scope of my invention as herein disclosed and claimed. 40

What I claim as my invention, and desire to secure by Letters Patent, is—

1. An improved thread-guide for a spinning-machine comprising an annular body part and two arms, on the body part of the guide, located substantially opposite to each other on said body part. 45

2. In combination in a ring-spinner, a ring supported in operative relation to a spindle and having a groove in its inner surface, and a thread-guide located in said groove with a plural number of arms located opposite to each other and projecting from the body part of the guide and with eyes or loops for the passage of the thread. 50

3. An improved thread-guide for a spinning-machine comprising an annular body part and a plural number of arms projecting on opposite sides thereof, one arm being longer than the other on the opposite side of the body part, and eyes or loops formed in the arms for the passage of a thread. 55

JACOB WIDMER.
